UNITED STATES PATENT OFFICE.

CALVIN NORMAN WHITE, OF MARICOPA, CALIFORNIA.

RADIATOR-CAP LOCK.

Application filed February 24, 1921. Serial No. 447,603.

To all whom it may concern:

Be it known that I, CALVIN NORMAN WHITE, a citizen of the United States, residing at Maricopa, in the county of Kern and State of California, have invented a new and useful Radiator-Cap Lock, of which the following is a specification.

An object of this invention is to provide a simple and effective means for locking a 10 radiator cap so that it cannot be removed from a radiator except by a person knowing the unlocking combination; and the purpose of this lock is to prevent thieves from stealing the radiator cap and its attachments. 15 It is common practice now in automobile construction to provide radiator caps with attachments such as ornamental figures, or a thermometer for indicating temperature of the radiator; and these attachments are 20 provided with threaded stems extending downward through the top of the radiator caps and are secured to said caps by nuts that are fully enclosed and not accessible for removal until the radiator cap is removed; 25 so that by locking the radiator cap in place both it and its attachments are secured against theft.

Other objects, advantages and features of invention may appear from the accompanying drawing, the subjoined detail description and the appended claims.

The accompanying drawing illustrates the invention.

Figure 1 is a central vertical section 35 through a radiator cap provided with this invention and attached to a radiator inlet pipe, showing parts in locked position.

Fig. 2 is a section similar to Fig. 1 showing parts in unlocked position.

Fig. 3 is a plan in section, on line x^3 , 40 Fig. 1.

Fig. 4 is a plan in section on line x^4 , Fig. 2.

Fig. 5 is a grouped plan and edge elevation of the stop disk.

Fig. 6 is a grouped plan and edge elevation of the upper lifting wedge.

Fig. 7 is a grouped plan and edge elevation of the lower lifting wedge.

Fig. 8 is a central section through the lock housing detached from the other parts.

Figs. 9 to 12 inclusive are diagrammatic fragmental views of the lock in various stages of operation for disengaging the plunger from the radiator locking lug.

Fig. 13 is a fragmental sectional view of

a modified form of radiator cap, the locking means however, being substantially the same as shown in Figs. 1 to 12.

The radiator 1, a portion of which is 60 fragmentally shown, is provided with an inlet pipe 2 that has either an internal or external thread as shown in Figs. 1, 2 and 13, and normally closed by a radiator cap 3 threaded thereto. 65

An attachment 4 that can be any ornamentation or useful appliance as the thermometer shown has a hub 5 from which extends the stem 6 with a reduced threaded end 7 that is fitted through a central opening 8 in cap 3; and is secured thereto by nut 9 and set screw 10. 70

Before attachment 4 is secured to cap 3 the locking parts are assembled as follows: lock housing 11, stop disk 12 and upper and 75 lower wedges 13, 14 are mounted on stem 6. Then with the face 15 of plunger 16 abutting the rim of wedge 14 the plunger 16 is extended into well 17 enclosed by housing 18 of cap 3; and the reduced threaded end 7 80 of stem 6 is extended through hole 8 and the parts secured together as heretofore described.

The housing 18 is provided with a ledge 19 on which the shoulder 20 of plunger 16 85 normally rests when in locked position.

Pipe 2 is provided with an inwardly extending lug 21 that is adapted to intercept the reduced lower end 22 of plunger 16 to prevent unscrewing when the radiator 90 cap is screwed into place on pipe 2 and the plunger 16 is released from wedges 13, 14 and drops by gravity into locking position with lug 21; that is interception of plunger 16 by lug 21 when cap 3 is turned in the 95 attempt of a thief to remove it, will prevent removal of the cap until the combination of the lock is set and wedges actuated to lift the plunger.

Plunger 16 is lifted and held out of engaging position with lug 21 by means of the wedges 13, 14 which when in predetermined position hold the plunger elevated so that cap 3 can be either screwed on or off of pipe 2. To lock cap 3 in place after it is screwed on 100 pipe 2 plunger 16 is disengaged from lifting wedges 13, 14 and falls by gravity as heretofore said into locking engagement with lug 21 so that the cap 3 and attached parts can not be removed until the plunger is again 105 lifted by means of the wedges.

Lifting wedges 13, 14 and also stop disk 12

are actuated by the indicator lock housing 11 which has integrally attached thereto a finger 23 that extends downward through concentric slot 24 in disk 12 into position to engage faces 25, 26 of wedge 13 and faces 27, 28 of wedge 14 by which these wedges are turned on the stem 6 either into position to lift plunger 16 or dislodge it from the wedges.

10 Lock housing 11 is provided with indicating numerals 29 that correspond in number to letters 30 on cap 3; and when certain predetermined numerals are moved into registering position with certain predetermined letters the disk 12 will be moved to a position whereby lifting wedges 13, 14 can be actuated to lift plunger 16 to disengage stop or lug 21.

15 It is understood of course that each lock 20 will have a different combination, that will require an alteration in position of the various parts functioning in the locking combination which parts consist of finger 23, connection slot 24, opening 31 in disk 12, plunger 16, and faces 25, 26, 27, 28 of 25 wedges 13, 14 all of which can occupy a multitude of positions around the axis of stem 6.

20 The combination herein provided for lifting plunger 16 out of engagement with lug 21 consists of the following movements of lock housing 11. As seen by dotted lines in Fig. 3 finger 23 is within the angle formed by Figures 6, 7 and axis of stem 6, so that 25 when the housing 11 is turned to the right to a position where 6, 7 register with f, g, it is known that lower wedge 14 has contacted with the rounded upper lip 32 of plunger 16 and lifted the plunger one step 30 in the unlocking movement. A further movement of the wedges is impossible owing to the position of disk 12 which obstructs a further upward movement of the plunger 16 sufficient to clear stop 21 until this disk 35 12 is turned backward or in the opposite direction by finger 23 until opening 31 in disk 12 is in axial alinement with the axis of plunger 16; consequently housing 11 must be turned or rotated to the left until numerals 6, 7 register with letters l, m, which 40 moves disk 12 so that the opening 31 is in the desired position. Then finger 23 is turned again to the right until 6, 7 registers with e, f at which time wedge 13 is actuated to lift plunger 16 the second and last 45 step in an unlocking movement; and when plunger 16 is supported on wedge 13 cap 3 can be unscrewed from nipple 2 as plunger 16 is lifted high enough to miss lug 23 as 50 cap 3 is screwed on or off of pipe 2.

55 When cap 3 is replaced on nipple or pipe 2 the housing 11 is turned to discharge plunger 16 from wedges 13, 14 after which it will fall by gravity into locking position 60 with lug 21.

The foregoing movement of parts for lifting plunger 16 is diagrammatically illustrated in Figs. 9 to 12 with wedges moving from left to right and disk 12 moving from right to left.

70 Fig. 9 shows plunger 16 in full locking position with lug 21. Fig. 10 shows the first step toward lifting plunger 16; that is wedge 14 has engaged and moved under lip 32 and lifted plunger 16 the width of wedge 14; also showing disk 12 in position to prevent wedge 13 from lifting plunger 16 a sufficient distance to disengage lug 21. Fig. 11 shows disk 12 moved to a position where the center of opening 31 registers with the 80 axis of plunger 16 making possible the final lifting movement of plunger 16 by actuation of wedge 13.

85 While this combination lock has been described as especially adapted to securing automobile caps against theft it is not intended to be limited to that purpose as it is equally adaptable to other uses.

I claim.

1. In a radiator cap lock, a pipe attached 90 to a radiator, a stop within said pipe, a cap for closing said pipe, a plunger in said cap for engaging said stop and provided with a lip; and means for engaging said lip to move said plunger out of engagement with 95 said stop.

2. In a radiator cap lock, a pipe attached to a radiator, a stop in said pipe, a cap for closing said pipe, a plunger in said cap for engaging said stop, an indicator housing 100 pivotally connected to said cap, and means actuated by said indicator housing for moving said plunger out of engagement with said stop.

3. In a radiator cap lock, a pipe attached 105 to a radiator, a stop in said pipe, a cap for closing said pipe, a plunger in said cap for engaging said stop, and wedges for moving said plunger out of engagement with said stop.

4. In a radiator cap lock, a pipe attached 110 to a radiator, a stop in said pipe, a cap for closing said pipe, a plunger in said cap for engaging said stop, wedges for moving said plungers out of engagement with said stop, 115 and an indicator housing on said cap for actuating said wedges.

5. In a radiator cap lock, a nipple attached to a radiator, a stop in said nipple, a cap for closing said nipple, a plunger in 120 said cap for engaging said stop, wedges for moving said plunger out of engagement with said stop, a stem secured to said cap, and an indicator housing pivotally connected to said stem for actuating said wedges to move said 125 plunger.

6. In a radiator cap lock, a nipple attached to a radiator, a stop in said nipple, a cap for closing said nipple, a plunger in 130 said cap for engaging said stop, wedges for

moving said plunger out of engagement with said stop, a stem secured to said cap, said stem having a housing attached thereto enclosing a thermometer, and an indicator housing pivotally connected to said stem, a finger on said indicator dial housing for engaging said wedges when said indicator dial housing is rotated on said stem.

7. In a radiator cap lock, a pipe attached to a radiator said pipe having an open threaded end, a lug within said pipe, a cap adapted to screw on and close said pipe, a plunger carried by said cap for engaging said lug after the cap has been placed on said pipe, a housing rotatably connected to said cap, and means operated by rotation of said housing for holding said plunger out of engagement with said lug while said cap is being screwed on or off of said pipe.

8. In a radiator cap lock, a pipe attached to a radiator said pipe having an open threaded end, a lug in said pipe, a threaded cap adapted to close said pipe, a plunger carried by said cap for engaging said lug after the cap has been placed on said pipe, a lip on said plunger, wedges for engaging said lip to lift said plunger out of engagement with said lug, and an indicator housing for actuating said wedges.

9. In a radiator cap lock, a pipe attached to a radiator said pipe having an open threaded end, a lug in said pipe, a threaded cap adapted to close said pipe, a plunger carried by said cap for engaging said lug after the cap has been placed on said pipe, upper and lower wedges for imparting a first and second lifting movement to said plunger, a disk opposing the lifting movement of the upper wedge, and means for moving said disk into position where it will not oppose the lifting movement of the upper wedge.

10. In a radiator cap lock, an inlet pipe attached to a radiator and having a threaded open end; a lug in said pipe; a cap adapted to screw on and close said pipe; a keyless lock comprising a plunger having a lip; and wedges adapted to engage said lip; said plunger being adapted to lock and unlock said cap by engagement with and disengagement from said lug.

In testimony whereof, I have hereunto set my hand at Los Angeles, California, this 15th day of February, 1921.

CALVIN NORMAN WHITE.
